DESIGN FOR A BUILDING

Carson Gary Starling, Orlando, Fla.

Application April 24, 1936, Serial No. 62,290

Term of patent 14 years

To all whom it may concern:

Be it known that I, Carson Gary Starling, residing at Orlando, in the county of Orange and State of Florida, have invented a new, original, and ornamental Design for Building, of which the following is a specification, reference being had to the accompanying drawing, forming a part thereof;

I claim:

The ornamental design for a building, as shown.

CARSON GARY STARLING.
